SOUND TRANSMITTING HEADSET

William D. Bowell, 705 S. 3rd St., Stillwater, Minn.

Filed Dec. 11, 1964, Ser. No. 82,987

Term of patent 14 years

(Cl. D26—14)

FIG. 1 is a front elevational view of a sound transmitting headset showing my new design, the rear being substantially a mirror image thereof;

FIG. 2 is an elevational view of the left side thereof;

FIG. 3 is an elevational view of the right side;

FIG. 4 is a top plan view;

FIG. 5 is a bottom plan view; and

FIG. 6 is an enlarged section view taken at substantially 6—6 of FIG. 1 and illustrating exterior contours not clearly visible in the other views.

This application is a continuation-in-part of my co-pending application, Serial Number D. 78,523 filed February 5, 1964, now abandoned.

I claim:

The ornamental design for a sound transmitting headset, as shown and described.
